EDWARD E. CLAUSSEN, OF HARTFORD, CONNECTICUT.

SANITARY COVER FOR TELEPHONE-MOUTHPIECES.

1,168,284.

Specification of Letters Patent. Patented Jan. 18, 1916.

Application filed October 27, 1914. Serial No. 868,830.

To all whom it may concern:

Be it known that I, EDWARD E. CLAUSSEN, a citizen of the United States, residing at Hartford, in the county of Hartford and State of Connecticut, have invented certain new and useful Improvements in Sanitary Covers for Telephone-Mouthpieces, of which the following is a specification.

This invention relates to sanitary covers for telephone mouth-pieces, the object of the invention being to provide an article of this character which is simple in construction, susceptible of easy and inexpensive manufacture, capable of ready and quick application to or removal from position and which when in active relation will be held against accidental displacement.

In the drawings accompanying and forming part of the present specification I have shown in detail one of the several convenient forms of embodiment of the invention, which to enable those skilled in the art to practice the same will be set forth fully in the following description. I do not restrict myself to this particular disclosure; I may depart therefrom in several respects within the scope of the invention.

In said drawings I also represent one of the many different ways of making the article.

Referring to said drawings: Figure 1 is a top plan view of a blank. Fig. 2 is an elevation of the blank drawn into cup form but not compressed. Fig. 3 is a perspective view of the finished article. Fig. 4 is an elevation of part of a telephone mouth-piece with the finished article applied thereto. Fig. 5 is a top plan view of two die members, one inclosed by the other. Fig. 6 is a sectional view of several die members showing how the article may be formed. Fig. 7 is a view with the upper die member of Fig. 6 omitted and a guide and a compressing member substituted therefor.

Like characters refer to like parts throughout the several views.

My cover is preferably made from sheet material, and I have found paper as eminently satisfactory for this purpose. When I employ paper as I prefer to do, the same may be of any quality or grade; as heavy in fact as cardboard, the weight not concerning the invention, although it should be sufficiently thin ordinarily as to facilitate its being bent as may be required in the process of forming the article from the blank to

finished condition. In Fig. 1 I have shown a blank as 2 such as meets my requirements, said blank consisting of a disk or circular piece of proper material. Approximately 60 centrally this blank may have a number of perforations 3 to facilitate the transference through the transmitter 4 of sounds which may be telephonically transmitted. In all cases these perforations may not be necessary. The exposed face of the blank may as shown bear upon its face advertising matter or anything else that may be desired. There may be cases where I should not prefer to form perforations in the blank, but, 70 where perforations are present, they can be made at the same time, the blank, by the aid of suitable dies, is being cut from the stock.

The finished article shown in Figs. 3 and 4 comprises a circular body as 5 which is inwardly dished or bulged as at 6, the inwardly-bulged portion 6 fitting within and frictionally engaging the wall of the customary tapered opening of the telephone mouth-piece 4. There may be instances where this 80 frictional engagement between the periphery of the bulge 6 and the wall of the transmitter opening will hold the cover in position, but I prefer to not rely upon this but to provide a more positive means for securing the cover 85 in place, the annular inturned flange 7 integral as shown with the circular body 5 answering efficiently in this regard, the flange being preferably expansible and contractible, so that it yieldingly grips the outer 90 portion of the transmitter 4 exteriorly thereof. This resilience or yieldability of the holding flange 7, which is shown as continuous, may be obtained in any desirable manner, although I have secured excellent results by fluting, creasing or plaiting said in-turned securing or holding flange 7, the plait extending depthwise of the flange. I find that by so making this flange it will provide a very satisfactory means for holding the cover in place, and it possesses under ordinary cases the requisite strength. For 95 additional security, however, I prefer to strengthen this flange, by densifying or compacting the same, this result being conveniently brought about by mashing down the flange, so that when thus operated upon it will be materially strengthened or reinforced without sacrifice of any of the yieldability circumferentially to which I have 100 alluded.

Not only is the flange strengthened or re-

inforced by the mashing down thereof in the manner alluded to, but the mashing action produces within the flange a corrugated surface or a surface having a multiplicity of 5 protrusions or as it might be otherwise stated, the flange is interiorly roughened so that it can obtain a firm hold on the exterior of the telephone mouth piece.

I have described one type of blank from 10 which the cuplike cover can be made. There may be instances in which this cover may be made in a radically different manner. I will hereinafter describe dies by which the article can be made. As will be inferred, 15 there may be cases where the cover can be made by entirely different means.

Referring now to Figs. 5, 6 and 7 in detail: The numeral 8 represents a cylindrical or tubular die member having in its upper 20 edge radial slots 9 by which teeth 10 are produced, the tops of these teeth being on upward, outward inclinations. Complementary to this die member 8 is a second and annular die member 11, the internal and external diameters of the two being similar, 25 the die member 11 having on its lower edge radial teeth 12 adapted to be projected into the tooth spaces or slots 9. In the construction shown the external diameter of the two die members 8 and 11 is practically the same 30 as that of the blank 2. Fitted within the tubular die member 8 is a core 19 having on its upper side the protuberance or boss 13. The purpose of the toothed portion of the 35 die members 8 and 11 is to plait marginally the blank 2 the function of the boss or protuberance 13 being to inwardly dish the blank as at 6.

In forming the article the following 40 procedure may be adopted: The blank 2 will be laid upon the die member 8 with the peripheries of the two coincident, after which the die member 11 will be brought over the die member 8 and said die members 11 and 8 45 will be relatively operated to cause the teeth 12 to project the marginal portion of the blank 2 slightly into the toothed spaces. The cylindrical plunger 14 will then be introduced into the annular die member 11 50 and projected downward, thereby downsetting the flange 7 and at the same time creasing or fluting the downset or flanged portion of the blank as shown in Fig. 2 which view represents the blank after the flange 7 has 55 been formed and plaited, the maximum

downward movement of the plunger or die member 14 not being requisite to form the plaited flange. On the continued downward movement of the core member 14 the central part of the stock of the blank will be forced 60 into the cavity 15 in the bottom of said core member by the boss 13, thereby producing the inward bulge 6 to which I have already alluded. The diameter of the core member 14 is less than the internal diameters of the 65 die members 8 and 11, so that the sleeve 16 can be fitted around the plunger or core member 14 after the blank has been flanged, plaited and bulged as set forth. This sleeve 16 can be lowered against the brim or rim 70 of the flange 7 and on being further advanced will act to mash down said flange and densify and reinforce it in the manner mentioned.

It will be noted that the bulge 6 is situated between the inner and outer edges of the circular retaining flange 7, the body 5 between the bulge and the flange being flat. The external portion of the bulge is upon a taper to adapt it to obtain a more secure 75 hold within the mouth piece 4. The flange 7 is of but a single thickness, so that I obtain the maximum gripping effect of the flutes or creases thereof.

What I claim is:

1. A sanitary one-piece cover of paper for telephone mouth pieces comprising a circular inwardly bulged body, the external portion of the bulge being upon a taper and being adapted to engage the inner surface 80 of the telephone mouth piece, said body having an inturned circular plaited flange between the inner and outer sides of which the bulge is situated, said flange being adapted to engage the exterior of the mouth piece 95 and the flange and the tapered portion of the bulge acting jointly to prevent accidental withdrawal of the cover from the mouth piece.

2. A sanitary one-piece cover of paper for 100 telephone mouth pieces comprising a body provided with a marginal circular plaited and mashed-down flange.

In testimony whereof I affix my signature in presence of two witnesses.

EDWARD E. CLAUSSEN.
